BIRD BATH

Joseph Karlik, Keyport, N.J., assignor to Morella's Lawn
Ornaments, Inc., Raritan, N.J., a corporation of New Jersey

Filed Feb. 7, 1962, Ser. No. 68,694

Term of patent 14 years

(Cl. D31—2)

The side not shown is substantially the same as the side shown.

The dominant features of my design reside in the portions shown in full lines.

I claim:

The ornamental design for a bird bath, as shown and described.
